(57) **CLAIM**

The ornamental design for refrigerator, as shown and described.

DESCRIPTION

FIG. 1 is a front top perspective view of the refrigerator with an opened door;

FIG. 2 is a front top perspective view of the refrigerator with a closed door;

FIG. 3 is a front view thereof;

FIG. 4 is a back view thereof;

FIG. 5 is a side view thereof;

FIG. 6 is another side view thereof;

FIG. 7 is a top view thereof;

FIG. 8 is a bottom view thereof; and,

FIG. 9 is a bottom perspective view thereof.

In some implementations, the top surface of the refrigerator includes a rectangular plate. In some implementations, a bottom portion of the refrigerator includes a compressor including a set of oval shaped openings.

The broken lines in each figure illustrate portions of the refrigerator that form no part of the claimed design.
